ELECTRICAL RELAY

Application filed February 2, 1931. Serial No. 512,928.

My invention relates to electrical relays, and particularly to electrical relays of the alternating current type responsive to current of one frequency but not to current of another frequency.

I will describe one form of relay embodying my invention, and will then point out the novel features thereof in claims.

In the accompanying drawings, Fig. 1 is a view, showing in front elevation, one form of relay embodying my invention. Fig. 2 is a top plan view, and Fig. 3 is a right hand end view of the relay shown in Fig. 1, with the contact structure removed.

Similar reference characters refer to similar parts in all three views.

Referring to the drawings, the reference character 1 designates a base plate which supports the operating mechanism of the relay. Attached to the base plate 1 are two upstanding posts 2 and 3 provided with trunnion screws 4 and 5, respectively, and mounted for rotation in these trunnion screws is a shaft 6 carrying a vane 7 of suitable electro-conductive material such as aluminum.

Cooperating with the vane 7 are two substantially U-shaped magnetizable cores 8 and 9. As best seen in Figs. 2 and 3, these cores are secured to the base plate 1 on opposite sides of the vane by means of suitable supports, here shown as brackets 10, and are arranged with the pole pieces of one core confronting the pole pieces of the other core but separated from the pole pieces of the other core by air gaps 11. These cores comprise a single magnetic circuit, and this magnetic circuit is energized by means of a winding 12 which I will term the "local" winding of the relay. This winding may be a single coil but, as here shown, it is constructed of two coils connected in series, one coil being located on each of the cores 8 and 9.

Also cooperating with the vane 7 is a third magnetizable core 13. This core is likewise substantially C-shaped, and the poles thereof are located on opposite sides of the vane adjacent the poles of the cores 8 and 9. As here shown, the core 13 is mounted on non-magnetizable supports 14, and is secured to the base plate 1 by means of screws 15, which ex-

tend downwardly through the core and through the supports, and which are threaded into the base plate 1. The core 13 is provided with an energizing winding 16 which I will term the "control" winding of the relay, and which for convenience, is made in two sections connected in series, one section being located on each side of the vane, as best seen in Fig. 2.

The portion of the relay mechanism thus far described is well known in the art and its operation is as follows. When the two windings 16 and 12 are supplied with alternating currents, the vane 7 is traversed by one magnetic flux, due to the flux which is set up in core 13 by the current in winding 16, and by two other magnetic fluxes due to the flux which is set up in cores 8 and 9 by the current in winding 12. The fluxes due to winding 12 induce currents in the vane, and if these currents and the flux due to winding 16 have the proper phase relations, these currents will react with the flux due to winding 16 to produce a torque on the vane which tends to rotate it. The direction of the vane rotation thus produced depends upon the relative polarity of the currents in the two windings 12 and 16, and may be reversed by reversing the relative polarity of the current supplied to winding 16. For purposes of the present description, I will assume that when the current is supplied to winding 16, it will be of such polarity that if winding 12 is then energized, the resultant torque which is exerted on the vane will tend to rotate the vane in a counter-clockwise direction, as viewed in Fig. 1.

Relays embodying my invention are particularly suitable for, although in no way limited to, use as track relays in signaling systems for electric roads in which the track rails, in addition to being supplied with signaling current at one frequency, usually 60 cycles per second, also serve as the return conductor for the propulsion current which is generally of a lower frequency such, for example, as 25 cycles per second. When a relay is used as a track relay in a system of this type, the local winding is supplied with current of the same frequency as the signaling

current from a transformer or other local source, while the control winding is connected with the track rails. Under some conditions, however, both windings of the relay may be supplied with current of either signaling frequency, or propulsion frequency, or both. It is desirable that the relay should operate when current of signaling frequency is supplied to the windings, but that the relay should not respond to current of propulsion frequency flowing in the windings. In order to obtain this desirable operation, I provide the relay with a fourth core 35 which also cooperates with the vane 7, and which is included in the field of the winding 16. The core 35 is substantially C-shaped, and, as here shown, is supported on non-magnetizable blocks 17 to which it is fastened by means of screws 19. The blocks 17, in turn, are mounted on top of the core 13, and are held in place by screws 18. The poles of the core 35 are located on opposite sides of the vane, preferably in such a position that one center line of each pole (the substantially vertical center line as viewed in Fig. 1) lies approximately on a radius of the vane; and each pole is provided with a ferrule 20 of copper or other electro-conducting material which partially encloses the pole face to produce a rotating magnetic field when the winding 16 is supplied with alternating current. This rotating magnetic field exerts a second torque on the vane, and the parts are so arranged that this torque will act in the opposite direction to and hence, will oppose, the main torque. Furthermore, each leg of the core 35 is surrounded by a short-circuiting band 21, the function of which will be made clear as the description proceeds. It will also be noted from an inspection of Fig. 2 that the air gap between the poles of the core 35 is smaller than the air gap between the poles of the core 13. The reason for this will likewise be made clear hereinafter.

A contact carrying rocker arm 22 (see Fig. 1) is pivotally mounted at 23 in suitable housings not shown in the drawings, and is provided with a substantially horizontal arm 24 which is pivotally connected with the upper end of a link 25. The lower end of the link 25 is pivoted on a pin 26 which is movable with the vane 7. As here shown, this pin passes through a jaw 27^a in an arm 27 which is attached to the shaft 6. The rocker 22 carries two contact fingers 28 and 29 which cooperate with two fixed contacts 28^a and 29^a, respectively, to close a contact 28-28^a or 29-29^a, as will be explained hereinafter. The rocker 22 also carries a bar 31 and a counterweight 34. The bar 31 cooperates with adjustable front and back stops 32 carried by a fixed block 33 to restrict the motion of the rocker 22 to the desired limits. The counterweight 34 serves to bias the rocker, and hence the vane, to a position in which

the contact 28-28^a is open and the contact 29-29^a is closed, as shown in the drawings.

The operation of the relay as a whole is as follows: When winding 12 only is energized, no torque is exerted on the vane, and the rocker 22 is then held, due to the bias of the counterweight 34 in the position in which the bar 31 engages the upper stop 32 as illustrated in the drawings. Under these conditions, contact 28-28^a is open and contact 29-29^a is closed. If, however, both of the windings 12 and 16 are energized by currents of the signaling frequency (say 60 cycles) upon which the relay is intended to operate, the reaction pointed out hereinbefore between the fluxes set up in the cores 8 and 9, due to the current in winding 12, and the flux set up in core 13, due to the current in winding 16, exerts a torque on the vane which tends to rotate the vane in a counter-clockwise direction. At the same time, a second or counter-torque is exerted on the vane by the rotating magnetic field set up by the flux in core 35. This counter-torque is small under these conditions, however, because this torque is proportional to the strength of the flux in the core 35, and the choking bands 21 on this core are so designed and the parts are so proportioned that at the signaling frequency, the counter-flux set up in the core 35 due to the electromotive forces which are induced in these bands will force most of the flux due to winding 16 through core 13. It will be apparent, therefore, that when both of the windings 12 and 16 are supplied with current of signaling frequency, the main torque will predominate and, as a result, the vane will rotate in a counter-clockwise direction until the bar 31 engages the lower stop 32, at which time further motion of the vane is prevented. Contact 29-29^a then becomes opened and contact 28-28^a becomes closed. The parts will then remain in these latter conditions until winding 16 is no longer supplied with the higher frequency current, at which time the parts will be returned to the positions shown by the bias of counterweight 34.

When windings 12 and 16 are energized, by current of propulsion frequency (say 25 cycles) the choking effect of the short-circuiting bands 21 is considerably less than when current of the signaling frequency is impressed on this winding and, since the air gap between the poles of core 35 is smaller than the air gap between the poles of core 13, most of the flux due to winding 16 then passes through core 35. It follows that, at the propulsion frequency, the counter-torque due to core 35 is very much larger than the counter-torque at the higher frequency and, as a result, while at low energization of winding 16, there may still be a slight torque tending to rotate the vane in a counter-clockwise direction, the parts are so proportioned that

this torque will be insufficient to overcome the bias of counterweight 34. As the voltage on winding 16 is raised, the counter-torque due to core 35 increases as the square of the applied voltage, while the main torque increases in direct ratio to the applied voltage. It will be apparent, therefore, that as the voltage in coil 16 at the propulsion frequency is raised, a point will be reached at which the counter-torque will completely balance the main torque and, if the voltage is raised beyond this point, the counter-torque will even exceed the main torque. It follows that the relay will not respond to current of the propulsion frequency in its windings.

If current of both propulsion and signaling frequencies is supplied simultaneously to the relay windings, the relay will operate to open contact 29-29^a and close contact 28-28^a in the manner previously described, provided the amount of the propulsion frequency current does not exceed a value which depends upon the proportioning of the parts (this value being greater than that ordinarily encountered in actual practice). If the amount of the propulsion frequency current does exceed this value, however, the counter-torque will become sufficiently large so that the vane will be held in the position in which contact 28-28^a is open and contact 29-29^a is closed.

It will be apparent from the foregoing that relays embodying my invention will respond to energizing currents of a particular frequency but will not respond to currents of other frequencies. In this connection, it should be pointed out that the relay as here shown discriminates against currents of lower frequency than the signaling current, but this arrangement is not essential.

Although I have herein shown and described only one form of electrical relay embodying my invention, it is understood that various changes and modifications may be made therein within the scope of the appended claims without departing from the spirit and scope of my invention.

Having thus described my invention, what I claim is:

1. A relay comprising a rotatable vane, two operating windings, means responsive to alternating currents in said windings for passing through said vane fluxes which co-operate to create a main torque on said vane which tends to rotate the vane in one direction, and means responsive to current in one said winding for creating a second torque which opposes said main torque and which is substantially equal to such main torque at one frequency of the current in said one winding but which is of lesser magnitude than such main torque at another frequency of such current.

2. A relay comprising a rotatable vane, means for inducing in said vane alternating

currents, a winding, means operating when alternating current is supplied to said winding for passing a flux through said vane which reacts with said induced currents in said vane to create a main torque on said vane which tends to rotate said vane in one direction, and other means operating when alternating current is supplied to said winding for applying to said vane a rotating magnetic field to produce a second torque which opposes said main torque and which equals said main torque at one frequency of the current supplied to said winding but which is of lesser magnitude than said main torque at another frequency of said current.

3. A relay comprising a rotatable vane, means for inducing in said vane alternating currents, a winding, means operating when alternating current is supplied to said winding for passing a flux through said vane which reacts with the induced currents in said vane to create a main torque on said vane which tends to rotate said vane in one direction, a core linking said winding and having two confronting poles separated by an air gap including said vane, a shading band partially enclosing the pole faces of at least one of said poles and operating when alternating current is supplied to said winding for applying to said vane a second torque which opposes said main torque, and means associated with said core and operating when current is supplied to said winding for regulating the flux in said core in accordance with the frequency of the current in said winding.

4. A relay comprising a rotatable vane, means for inducing in said vane alternating currents, a winding, means effective when said winding is supplied with alternating current for passing a flux through said vane which reacts with the induced currents in said vane to create a main torque on said vane which tends to rotate said vane in one direction, a core linking said winding and having two confronting poles separated by an air gap including said vane, a shading band partially enclosing the pole face of at least one of said poles and effective when alternating current is supplied to said winding for applying to said vane a second torque which opposes said main torque, and means associated with said core and effective when current is supplied to said winding for regulating the flux in said core in such manner that said second torque is substantially equal to said main torque for one and only one frequency and magnitude of the current in said winding.

5. A relay comprising a rotatable vane, means for inducing in said vane alternating currents, a winding, means effective when alternating current is supplied to said winding for passing a flux through said vane which reacts with the induced currents in

said vane to create a main torque on said vane which tends to rotate said vane in one direction, a core linking said winding and having two confronting poles separated by an air gap including said vane, a shading band associated with at least one of said poles and effective when alternating current is supplied to said winding for applying to said vane a second torque which opposes said main 10 torque, and means associated with said core and effective when current is supplied to said winding for reducing the flux in said core as the frequency of the current in said winding increases.

15 6. A relay comprising a rotatable vane, means for inducing in said vane alternating currents, a winding, means operating when alternating current is supplied to said winding for passing a flux through said vane which reacts with the induced currents in said vane to create a main torque on said vane which tends to rotate said vane in one direction, a core linking said winding and having two confronting poles separated by an air gap including said vane, a shading band associated with at least one of said poles and operating when alternating current is supplied to said winding for applying to said vane a second torque which opposes said main 25 torque, and at least one short-circuiting band associated with said core for regulating the flux in said core when current is supplied to said winding in accordance with the frequency of the current in said winding.

30 35 7. A relay comprising a rotatable vane, means for inducing in said vane alternating currents, a winding, means effective when alternating currents are supplied to said winding for passing a flux through said vane which reacts with the induced currents in said vane to create a main torque on said vane which tends to rotate said vane in one direction, a core linking said winding and having two confronting poles separated by an air gap including said vane, a shading band associated with at least one of said poles and effective when alternating current is supplied to said winding for applying to said vane a second torque which opposes said main 40 torque, and at least one short-circuiting band associated with said core and effective when current is supplied to said winding for regulating the flux in said core in such manner that said second torque is substantially equal 45 to said main torque for one and only one frequency and magnitude of the current in said winding.

50 55 60 8. A relay comprising a rotatable vane, means for inducing in said vane alternating currents, a winding, means operating when alternating current is supplied to said winding for passing a flux through said vane which reacts with the induced currents in said vane to create a main torque on said 65 vane which tends to rotate said vane in one

direction, a core linking said winding and having two confronting poles separated by an air gap including said vane, a shading band associated with at least one of said poles and effective when current is supplied to said winding for applying to said vane a second torque which opposes said main torque, and at least one short-circuiting band associated with said core and operating when current is supplied to said winding for reducing the flux in said core as the frequency of the current in said winding is increased.

9. A relay comprising a rotatable vane, a first core having two confronting poles separated by an air gap including said vane, a winding associated with said core for setting up alternating fluxes in said core which thread said air gap, means for inducing in said vane alternating currents which react with the fluxes in said air gap to create a main torque on said vane which tends to rotate said vane in one direction, a second core linking said winding and having two confronting poles separated by an air gap including said vane, a shading band associated with at least one pole of said second core and effective when alternating current is supplied to said winding for applying to said vane a second torque which opposes said main torque, and means for regulating the strength of said second torque in accordance with the frequency of the current in said winding.

10. A relay comprising a rotatable vane, a first core having two confronting poles separated by an air gap including said vane, a winding associated with said core for setting up alternating fluxes in said core which thread said air gap, means for inducing in said vane alternating currents which react with the fluxes in said air gap to create a main torque on said vane which tends to rotate said vane in one direction, a second core linking said winding and having two confronting poles separated by an air gap including said vane, a shading band associated with at least one pole of said second core and effective when alternating current is supplied to said winding for applying to said vane a second torque which opposes said main torque, and at least one short-circuiting band on said second core for regulating the flux in said second core in accordance with the frequency of the current in said winding.

11. A relay comprising a rotatable vane, a first core having two confronting poles separated by an air gap including said vane, a winding linking said core for setting up in said core alternating fluxes which thread said air gap, means for inducing in said vane alternating currents which react with the fluxes which are created in the air gap between the poles of said first cores to create a main torque on said vane which tends to rotate said vane in one direction, a second core linking said winding and having two

confronting poles separated by an air gap including said vane, a shading band surrounding a portion of at least one of the poles of said second core and effective when alternating currents are supplied to said winding for applying to said vane a second torque which opposes said main torque, and at least one short-circuiting band on said second core, said band and the air gaps between the poles of said cores being so proportioned that when alternating current at one frequency is supplied to said winding, most of the flux due to said winding will flow through said one core but that when alternating current at another frequency is supplied to said winding, most of the flux due to said winding will flow through said other core.

In testimony whereof I affix my signature.
BERNARD E. O'HAGAN.
